LAMP HOLDER FOR TUBULAR ELECTRIC LAMPS WITH AXIALLY PROJECTING CONTACTS

Gunnar Fridolf Axberg, Enskede, Sweden, assignor to Lumalampan Aktiebolag, Stockholm, Sweden, a corporation of Sweden

Application April 21, 1948, Serial No. 22,458
In Norway March 16, 1948

2 Claims. (Cl. 173—328)

1

This invention relates to a lamp holder for tubular electric lamps with axially projecting contact prongs.

The object of the invention is to provide a holder construction the separate elements of which are easily assembled and interlocking themselves without any further locking or fastening means thus bringing about a simplified manner to manufacture such devices.

In carrying out the invention two oppositely disposed spring contact members are mounted on a carrier in an insulating housing moulded into an integral piece and forming a cavity. A rotatable support for the tube prongs or the like is mounted between the contact springs in the housing. As known heretofore the support is provided with a transverse groove and one edge of the housing is provided with an entrance groove to guide the prongs into the open circuit position. According to the invention this support is inserted through a circular opening in a face of the housing and provided with end flanges of which the outer flange is adapted to fill in the opening of the housing. The waist portion of the support has a length equal to the width of the contact springs to prevent axial displacement of the support. The support being pivotally supported within the opening of the housing thus serves as sole implement to interlock the housing and the inserted contact spring carrier in cooperation with these springs anchored into the carrier.

A number of important details of construction will be more fully described hereinafter.

Fig. 1 is a front view in section of a lamp holder embodying one form of the invention, the support being shown in the open circuit position.

Fig. 2 is a part of a further front view showing the support in the closed circuit position.

Fig. 3 is a longitudinal sectional view, the support being shown in the position for the lamp base insertion.

Fig. 4 is an end view of the lamp holder.

Fig. 5 is a perspective view of the holder housing.

Fig. 6 is a perspective view of the contact spring carrier with the contact springs anchored in recesses into the carrier.

Fig. 7 is a perspective view of the support.

Fig. 8 is a longitudinal sectional view showing the lamp holder partially assembled and the mode of assembly.

The housing 8 has a widened base section 24 at the side facing the lamp and is moulded of insulating material into an integral piece. Inside of the housing is a cavity or chamber 9 open at the base of the housing. Through this base opening 1 is inserted a carrier body 2 moulded of insulating material and supporting

two contact spring members 10, 10. Two projections 6, 6 are disposed on the carrier 2 resting against suitable projections 25, 25 formed into the widened base part 24 of the housing. The latter projections are provided with downward openings 23, 23 for screws to fasten the lamp holder on the lamp fitting or the like.

Each spring contact member 10, 10 consists of a metal strip the foot end of which is rolled up into a tubular sleeve 4 and through the sleeve wall is threaded a clamp screw 3 for fastening a lead-in wire. By means of these sleeve portions 4, 4 the contact springs 10, 10 are anchored in recesses 7, 7 into the carrier body, said recesses being formed adequately to the shape of said end portions of the strips and opened downwards for the clamping of the screws 3, 3. Between the two springs 10, 10 the carrier body forms a boss portion 20 which separates the two springs.

The base part of the housing is provided with two "knock outs" 22, 22 for enabling supply conductors to be inserted from the front or the back end of the holder, the bottom of the carrier body 2 being provided with a groove 5 for the conductors inserted from the back of the holder.

The supporting member 29 has two end flanges 15, 28 of which the outer one 28 is rotatably mounted in a circular opening 27 in the front of the housing 8. The length of the waist portion 14 of the support is equal to the width of the spring contact strips 10, 10 whereby the axial displacement of the support 29 when introduced through the opening 27 and mounted between the contact springs 10, 10 is prevented. The width of the spring contact carrier 2 corresponds to the inner width of the main portion 10 of the housing 8 and is thereby securely rested within the housing. The waist portion 14 of the support 29 is provided with conventional projections 12, 12 oppositely disposed and the contact springs are provided with corresponding pocket portions 13, 13. The support thus will serve as a suitable implement to interlock the housing and the carrier body by means of the contact springs anchored into the carrier. At the assemblage of the elements composing the lamp holder the support is introduced through the front opening of the housing and the carrier is inserted into the base opening of the cavity of the housing. When the contact springs with their pocket portions resiliently embrace the waist section of the support all elements are sufficiently interlocked so that no further means are necessary for fastening them together. This arrangement substantially simplifies the manufacturing of the lamp holder.

50 The front part of the support 29 is provided

55

with a conventional groove 13 in a plane intersecting that of its projections 12, 12 and adapted to receive the prongs 11, 11 of the lamp tube 10 or other device which is supported by the holder. The housing is provided too with a conventional entrance groove 17 leading to the groove in the rotatable support.

In Fig. 1 the lamp tube is shown with its contact prongs 11, 11 inserted before rotating of the tube and the support; the projections of the support are clamped by the contact springs and rested in their pocket portions. In Fig. 2 the tube is shown as when rotated and the contact spring pockets gripping the prongs of the tube. In all positions the contact springs will prevent the axial displacement of the support.

To further secure the position of the support a rear wall prolongation 21 of the carrier body 2 may be provided as shown in Figs. 1 and 3. This wall 21 is rested on the rear inside 26 of the cavity 9 in the housing and is provided with a circular opening 19 corresponding to the inner flange 15 of the support 29.

Alternatively or in combination with this construction the inner flange 15 of the support can be provided with a cylindrical boss 30 adapted to be supported in a corresponding recess 31 in the inside wall 26 of the housing opposite to the front opening 27 of the same.

As shown in Fig. 8, the lamp holder of this invention is assembled by partially inserting the support 29 into the housing 8 through the aperture 27 with the flange 15 of the holder 29 positioned within the interior of the housing 8. At this time the carrier 2 is inserted lengthwise into the housing with the spring contact fingers 10 engaging the flange 15 on the support 29. The carrier 2 is moved inwardly of the housing 8 until the aperture 19 in the rear wall 21 of the carrier 2 is in axial alignment with the aperture 27 in the housing 8. At this time the contact fingers 10 will embrace the flange 15 of the support 29 and such support may be moved axially until the boss 30 is disposed in the recess 31 in the rear wall of the housing 8, at which time the flange 15 will be disposed in the aperture 19 in the wall 21 of the carrier 2 and the spring contact fingers 13 will snap into the reduced portion 12 between the flanges 15 and 23 on the support 29, thus securing the parts of the lamp holder together. If desired, suitable jigs and fixtures may be utilized in the assembly operation, but such jigs or fixtures are not necessary since the parts may be assembled by purely hand manipulative operations. As a result of the structure of the lamp holder of this invention and the assembling process above described, it will be seen that all of the parts of the lamp holder are retained in assembled position merely by the resilient engagement of the spring contact fingers 10 in the reduced portion 12 between the flanges 15 and 23 on the support 29.

From the above description, it is evident that holder construction composed of elements which the invention has provided an improved lamp are easily assembled into a permanently inter-fixed structure without use of any additional means for their fastening together, the elements necessary to construct a lamp holder for the purpose specified solely interlocking themselves into such assembled permanent structure.

What I claim is:

1. A holder for tubular electric lamps with axially projecting contact prongs comprising a one-piece elongated hollow housing open at one end, a carrier disposed in said housing, resilient elongated contacts secured to said carrier within said housing and terminating adjacent the end opposite said open end, a substantially circular aperture in one wall of said housing, said carrier having a portion extending along an opposite wall of said housing toward the end opposite said open end, a substantially circular aperture in said portion of said carrier and in axial alignment with said first-mentioned aperture, a slot in the end wall of said housing opposite said open end and communicating with said apertures, a lamp supporting member having flanges adjacent opposite ends rotatably mounted in said apertures and a reduced intermediate portion formed by said flanges, a recess formed in the wall of said holder opposite said first mentioned aperture, the flange at one end of said supporting member having a cylindrical boss rotatably mounted in said recess, a diametrically disposed groove in the opposite end portion of said supporting member for receiving said prongs, said contacts partially embracing said reduced intermediate portion between said flanges, the engagement between said housing, carrier, and supporting member serving to retain the holder in assembled relationship.

2. A holder for tubular electric lamps with axially projecting contact prongs comprising a one-piece elongated hollow housing open at one end, a carrier disposed in said housing, resilient elongated contacts secured to said carrier within said housing and terminating adjacent the end opposite said open end, a substantially circular aperture in one wall of said housing, said carrier having a portion extending along an opposite wall of said housing toward the end opposite said open end, a substantially circular aperture in said portion of said carrier and in axial alignment with said first-mentioned aperture, a slot in the end wall of said housing opposite said open end and communicating with said apertures, a lamp supporting member having flanges adjacent opposite ends rotatably mounted in said apertures and a reduced intermediate portion formed by said flanges, a diametrically disposed groove in one end portion of said supporting member for receiving said prongs, said contacts partially embracing said reduced intermediate portion between said end flanges, the engagement between said housing, carrier, and supporting member serving to retain the holder in assembled relationship.

GUNNAR FRIDOLF AXBERG.
